CLAIM

The ornamental design for an underbody lamp, as shown and described.

DESCRIPTION

FIG. 1 is a perspective view of an underbody lamp showing our new design;

FIG. 2 is a front view thereof;

FIG. 3 is a back view thereof;

FIG. 4 is an enlarged left view thereof; with the right view being a mirror image thereof; and,

FIG. 5 is a top view thereof; with the bottom view being a mirror image thereof.

The broken lines shown on the drawings depict portions of the underbody lamp that form no part of the claimed design.
